(57) **CLAIM**

The ornamental design for a vehicle front portion, as shown and described.

DESCRIPTION

FIG. 1 is a perspective view of a vehicle front portion showing our new design;

FIG. 2 is a side elevational view of one side thereof;

FIG. 3 is a side elevational view of the other side thereof; and,

FIG. 4 is a front elevational view thereof.

The broken line showings of the wheels, tires and lozenge shape, and the remainder of the vehicle exterior form no part of the claimed design.
